UNITED STATES PATENT OFFICE.

AUGUST SUNDH AND DAVID LEONARD LINDQUIST, OF YONKERS,
NEW YORK.

ELECTROMAGNET-SWITCH.

SPECIFICATION forming part of Letters Patent No. 792,859, dated June 20, 1905.

Application filed October 27, 1904. Serial No. 230,267.

To all whom it may concern:

Be it known that we, AUGUST SUNDH and DAVID LEONARD LINDQUIST, of Yonkers, Westchester county, New York, have invented a new and useful Improvement in Electromagnet-Switches, of which the following is a specification.

The invention relates to an electromagnet-switch constructed to be operated by alternating current.

The object of the invention is to prevent hammering or chattering of the armature when attracted by the magnet.

In another application for Letters Patent, Serial No. 230,266, simultaneously filed herewith, we have described and broadly claimed the combination, with a source of alternating current, of an electromagnet-coil energized thereby, an armature therefor constructed to be moved into a position of magnetic equilibrium, a circuit-closing device controlled by said armature, and a resilient abutment constructed to absorb the vibrations of said armature when in said equilibrated position, due to current alternations in said coil.

Our present invention consists in a special construction of said electromagnet in which we employ an armature having an opening constructed loosely to receive a pole-piece on the magnet-core, the said armature being arranged to swing, and also in the combinations more particularly set forth in the claims.

In the accompanying drawings, Figure 1 is a section of our single-phase alternating-current magnet on the line $\alpha\alpha$ of Fig. 2. Fig. 2 is a side elevation showing also electrical connections in diagram. Fig. 3 is a top view. Fig. 4 is a section on the line $\gamma\gamma$ of Fig. 1. Fig. 5 shows a modification in the form of circuit-terminal.

Similar numbers of reference indicate like parts.

1 represents the supporting base-plate.

2 is the magnet-coil, extending through which is the laminated core 3, having two projections 5 and 6, which extend, respectively, above and below said coil.

Secured to the plate 1 by a bolt 7 is a bracket 8, having an integral arm 9, Fig. 4,

provided with a lug 10 on its upper side. A 50 separate and similar bracket-arm 11 is provided with a similar lug 12. The upper projection 5 of the laminated core 3 is placed between the bracket-arms 11 and 9 and clamped by means of the headed bolt 13, which passes 55 through the lugs 10 and 12 and is secured by a nut. A similar bracket 14, having an integral arm and a separate arm, is also secured to the supporting-plate 1 below the bracket 8, and in like manner between said arms is 60 clamped the lower projection 6 of the core 3. The lugs on the under side of the arms of bracket 14 are extended, as shown at 15, to receive the pivot-pin 16 of the swinging armature-frame 17. Said frame has two arms 65 19 and 20, which receive between them the laminated armature 21, which is clamped between said arms by means of the bolts 22 passing through lugs 23. The arm 20 at its upper end is turned at right angles to meet the 70 arm 19, so that said arms, together with the lugs on bracket 14 and the collar 18, carried by the pivot-pin, form the quadrangular frame 17. In the armature is an opening 24, which when the frame 17 is swung toward the magnet 75 receives the polar extremity 25 of the upper projection 5 of the laminated core. The opening 24 is sufficiently large to permit the pole-piece 25 to enter it freely without touching the sides.

Through the turned upper portion of the arm 20 passes a threaded sleeve 26, and through said sleeve passes a threaded rod 27, secured by nut 27^x. Loose on said rod 27 is a circuit-closer plate 28, outside of which is a stop-pin 85 29. Between plate 28 and sleeve 26 is interposed a helical spring 30, which normally presses the plate 28 outward against pin 29. A set-screw 31^x passes through the upper end of frame-arm 19 and enters arm 20 sufficiently 90 to bear against the thread of sleeve 26. The sleeve 26 may be adjusted longitudinally to vary the tension of helical spring 30 and when adjusted is jammed by setting in the screw 31^x and so held as placed.

Secured to the supporting-plate 1 are two brackets 31 32, each carrying a threaded contact-terminal 33. The ends of said brackets are

forked and provided with clamping-screws 34 for holding said terminals in adjusted position. The brackets 31 32 may be connected, as shown in Fig. 2, in a circuit, which also 5 includes a solenoid 35, controlling a circuit-closer 36, whereby circuit may be established through translating devices, such as electric lamps, (indicated at 37.) The terminals of the magnet-coil may be connected to a secondary coil 38, disposed in inductive proximity to a primary coil 39, energized from any suitable source 40 of single-phase alternating current.

The operation of the device is as follows: 15 When the magnet-coil is energized, the armature is attracted and the frame 17 swings inward, so that the pole-piece 25 enters the opening 24. The circuit-closing plate 28 then meets the terminals 33, thus establishing the 20 circuit shown in Fig. 2 and causing the solenoid 35 to close circuit.

It will be apparent that by reason of the foregoing construction the pull of the pole-piece 25 upon the armature rapidly decreases 25 in strength as the pole-piece enters the armature-opening, so that it is weakest when the plate 28 is in contact with the terminals 33. Hence the influence of changes in current strength upon the armature is then reduced 30 to a minimum.

Particular attention is called to the fact that the armature when in attracted position does not come in contact with any rigid or unyielding abutment and that, on the contrary, 35 its only abutment is then a resilient or elastic body—to wit, the spring 30, which spring both receives the thrust of the armature due to the magnetic pull and acting in the direction of the path of movement of the circuit-closing plate 28 toward terminal 33 also absorbs the vibrations of said armature due to current alternations in the electromagnet-coil, thus preventing the communication of 40 said vibrations to said circuit-closing plate.

45 Instead of arranging the terminals 33 in brackets, as described, we may arrange them as shown in Fig. 5. Here the terminals of dovetail section are disposed in holding-plates 41, which slide freely on pins 42, which extend from plates 43, bolted to the supporting-plate 1. Said plates 41 are set outwardly by helical springs 44 against stop-pins 45. The 50 springs 44 then coact with the helical spring 30 in taking up the armature vibrations and 55 forming a resilient abutment.

We claim—

1. A source of alternating current, an electromagnet-coil energized thereby, a support, an armature, pivoted at one end to said support and extending in front of a pole of said magnet and movable on its pivot to a position of magnetic equilibrium, a resilient body wherewith said armature establishes contact when moved to said position, and a circuit-

closer controlled by said armature; the said resilient body being constructed to take up the vibrations of said armature due to current alternations in said coil. 65

2. A source of alternating current, an electromagnet-coil energized thereby, a support, 70 an armature pivoted at one end to said support and extending in front of a pole of said magnet and movable on its pivot to a position of magnetic equilibrium, a resilient body wherewith said armature establishes contact 75 when moved to said position, means for varying the resiliency of said body, and a circuit-closer controlled by said armature; the said resilient body being constructed to take up the vibrations of said armature due to current 80 alternations in said coil.

3. A source of alternating current, an electromagnet-coil energized thereby, an armature pivoted to a polar extremity of the core of said coil and extending in front of the 85 other polar extremity of said core, and movable on its pivot to a position of magnetic equilibrium, a resilient body wherewith said armature establishes contact when moved to said position, and a circuit-closer controlled 90 by said armature; the said resilient body being constructed to take up the vibrations of said armature due to current alternations in said coil.

4. A source of alternating current, an electromagnet energized thereby, a projecting pole-piece on said magnet, a movable armature having an opening loosely receiving said pole-piece, a circuit-closer controlled by said armature and a resilient abutment receiving 100 the thrust of said armature and constructed to absorb the vibrations thereof due to current alternations in said coil. 95

5. A source of alternating current, an electromagnet energized thereby, a projecting pole-piece on said magnet a swinging armature having an opening loosely receiving said pole-piece, a circuit-closer carried by said armature and a spring interposed between said circuit-closer and said armature; the said 105 spring forming an abutment for said armature and constructed to absorb the vibrations thereof due to current alternations in said coil. 110

6. An electromagnet-coil, a fixed core therefor having a laterally-extending pole-piece, a 115 swinging armature provided with an opening constructed loosely to receive said pole-piece, a circuit-closing plate on said armature and a spring supporting said plate and forming a resilient abutment for said armature. 120

In testimony whereof we have signed our names to this specification in the presence of two subscribing witnesses.
